US0D1061753S

(12) United States Design Patent (10) Patent No.: US D1,061,753 S
(45) Date of Patent: * Feb. 11, 2025

(54) STAFF

(71) Applicant: Tracy Anderson Mind and Body, LLC, New York, NY (US)

(72) Inventors: Tracy Anderson, New York, NY (US); Paul Dowd, New York, NY (US); Carl Ranieri, III, New York, NY (US); Josh Goldin, New York, NY (US)

(73) Assignee: Tracy Anderson Mind and Body, LLC, New York, NY (US)

() Term: 15 Years

(21) Appl. No.: 29/882,975

(22) Filed: Jan. 20, 2023

(51) LOC (15) Cl. 21-02

(52) U.S. Cl.

USPC D21/679; D21/662; D21/691; D21/797; D21/798
